Charles G. Hensley

UNITED STATES PATENT OFFICE

FRANÇOIS R. MARCEL, OF BROOKLYN, NEW YORK

CURLING IRON

Application filed September 3, 1931. Serial No. 560,978.

My invention relates to curling irons and especially to irons for curling the human hair to produce various wave effects, and especially to produce what is known as a Marcel wave.

5 In the formation of the Marcel and other waves it is desirable to produce curves in the hair of various sizes. In some cases hair dressers have been provided with curling irons having different size prongs and spoons,

10 some of which have been designated the C irons and the D irons, according to their sizes. This necessitated the use of more than one iron for producing the desired waves and it is obvious that that method was but a makeshift and was very annoying and troublesome. Even where this method was used it was only partially satisfactory because the operator was limited to two sizes corresponding with the curvatures of the two irons used.

15 One object of the present invention is to provide a curling iron which can be manipulated to produce various size curves with a single iron. This is made possible by making the rod member of the iron revolvable

20 and by providing a handle on the extension or tang of the rod member by means of which the operator may cause the rod member to be revolved, thus causing the lock of hair which is gripped between the spoon and rod mem-

25 bers to be rolled through between these members for producing a wave which is greater than the fixed size of the iron.

In addition, the rolling action of the rod member causes the lock of hair to be more 30 completely worked in by the iron so that a more lasting wave is produced than with the irons previously used.

An incidental advantage of the present device is that where the iron is of the electrical- 35 ly heated type with the electric heating unit disposed in the rod member, the cable cord by which the heater is connected with the source of current does not become entangled in the manner previously experienced with 40 other irons. Former irons were twisted pro- gressively in the same direction during the waving of the hair, causing the cable to be twisted unless the operator stopped in the waving process and turned the iron back to 45 unwind the cable. With the present device

the rod member will generally be revolved re- versely during the waving of the hair, so that twisting of the cable in one direction is offset by the twisting of it in the opposite direc- 55 tion. Furthermore, the rod member may be twisted while the iron is held in the hand without turning the iron around as a whole, thus facilitating the unwinding of any twist in the cable.

Another object of my invention is to com- 60 bine the revolving feature of the rod member with an iron of the flange type, such as is shown in my Letters Patent No. 1,277,739. Where the rod member is provided with a flange to overlap one of the edges of the spoon 65 member for the purpose of producing and setting a reverse wave in the formation of the well known Marcel wave, the revolving action referred to, of the rod member, materially improves the action of the flange member and 70 also works the lock of hair into position to be more completely heated so that the wave is more lasting.

In this type of iron it is preferable to limit 75 the extent of rotation of the rod member and I have provided means for this purpose. Other advantages will be apparent from the following detailed description of my inven- tion.

In the drawing forming part of this appli- 80 cation,

Figure 1 is an elevation of a hair waving iron embodying my invention, said iron being adapted to be heated other than by an electric unit, and is generally called a gas 85 iron.

Figure 2 is an end view thereof looking at the iron as indicated by the line 2-2 of Figure 1, both Figures 1 and 2 showing the iron 90 in closed position,

Figure 3 is a sectional view taken on the line 3-3 of Figure 2, showing the iron opened,

Figure 4 is an elevation of part of a curl- 95 ing iron of the flange type and embodying the features of my present invention,

Figure 5 is a cross sectional view taken on the line 5-5 of Figure 4,

Figure 6 is a sectional view taken on the 100 line 6-6 of Figure 4,

Figure 7 is an inverted plan view of the hinge portion of the iron.

Figure 8 is a sectional view taken on the line 8—8 of Figure 4, and

5 Figure 9 is an elevation of a portion of an iron of the electrically heated type.

I will first describe the form of the invention shown in Figures 1 to 3. In this type of iron there is a curved or hollowed member 10 which might be called a spoon; and it has a convex surface 2 adapted to receive therein in a portion of the rod member.

The spoon member has a yoke 3 formed at one end of the spoon proper, the yoke being 15 adapted to straddle the bearing member of the rod member and the yoke curves upwardly and comes together to form a handle member 4. This handle member is usually covered with a grip portion 5 made of fibre or 20 other heat insulating material. This is one of the co-operating handles by which the iron is manipulated.

The rod member is shown as including a straight, circular rod 6 which is of such diameter as to fit closely within the curved surface of the spoon member for the purpose of pressing the hair therein. This rod member is provided with a large bearing member 7 which extends through the opening of the yoke 3 and is pivotally mounted therein in any desired way such as by the indentations 8 punched in the side walls of the yoke, the punched portions projecting into the ends of the bore 9 extending crosswise through the bearing member 7.

The rod member extends through the bearing member and its rear end 10 forms a handle in co-operative relation with the handle of the spoon member. There is a collar 11 secured on the rod member adjacent one end of the bearing member 7 and secured to the rod by means of the set screw 12, by welding or any other manner, so that it cannot shift on the rod. Near the other end of the bearing member there is a sleeve 13 forced onto the handle 10 of the rod member, and this has an outwardly flared end 14 which abuts against the end of the bearing member 7 opposite to the collar 11 and prevents the axial movement of the rod member in relation to the bearing member. It is sufficient for this sleeve to be applied to the rod by a driving fit. There is a grip member 15 preferably of fibre or other heat insulating material, which is driven onto the sleeve 13 and the outer surface of this grip member is polygonal, as shown in Figure 1, in order to permit the hand to grip it and cause it to be revolved.

The rod member, it will be observed, is 60 pivotally connected with the spoon member because the bearing member 7 is pivotally mounted on the members 8 and can swing in a vertical plane in relation to the spoon member. As the rod member is mounted in the 65 bearing member it swings or pivots with it

so that the portion 6 of the rod may move toward and from the convex side of the spoon member similar to the jaws of pliers. The rod member cannot shift axially to any great extent within the bearing member 7 but it 70 fits loosely in the bore of this member so that the rod member may revolve freely within the bearing member.

Operation

75

The iron, to a certain extent, will be handled and manipulated very much the same as an ordinary curling iron except that when the rod and spoon members have been closed upon a lock of hair passing between these members the operator may turn the handle 15 and as this is fixed to the sleeve 13 and the sleeve is fixed on the shank 10 the rod member will be revolved within the bearing member 7. This will have the effect of rolling the hair through or between the rod and spoon members while the latter are pressing against the lock of hair. The rod member may be revolved first in one direction to propel the hair between the rod and spoon in one direction and then reversed and turned in the opposite direction about the same extent to propel the hair back.

The width (distance from crest to crest) of the wave made in this manner is not necessarily limited to the width of the iron but it may be much greater owing to the fact that the lock of hair is propelled between the spoon and rod while pressed between them. It is thus within the control of the operator to 100 make the wave as wide as desired by simply manipulating the handle 15 to revolve the rod member more or less.

Of course, it is optional with the operator to revolve the rod member or leave it stationary. The rod turns very easily within the bearing member 7, and therefore the handle 15 may be turned very easily. The rod member is always in condition to be rocked on the pivot 8 for moving the rod and spoon members toward and from each other independently of the revolving movement of the rod member.

In Figures 4, 5, 6 and 8 I have shown the invention incorporated with the features of 115 the flange iron shown in my said patent. In this construction the spoon member is the same as the one just described, and the parts are designated by similar reference numerals. The rod member in this case consists of a 120 cylindrical portion 17 having a flange 18 projecting at one side thereof to overlap one edge 19 of the spoon member when the iron is closed, in order to heat the part of the hair which is curled about this edge, as well as 125 to press the hair around the edge of the spoon to form a reverse wave. The function and action of this flange member are well known in the art and are fully set forth in my said patent. The flange terminates ahead of the 130

bearing member 7 so that the rod member is circular where it passes through this member. It therefore corresponds to the rod member in the previous construction. The bearing member 7 is pivoted between the arms of the yoke 8 the same as before, and the rod member is adapted to revolve in the bearing member. The rear ends or handle portions of the spoon and rod members are provided with 10 grips 5 and 15, the latter being polygonal for the same purpose as previously described. Inasmuch as the flange 18 of the rod member should not be turned into the concave side of the spoon member, I have provided means 15 for limiting the revolving motion of the rod member, so that the flange will always lie outside of the spoon and in one position will overlap one of its edges.

It will be observed that there is a pin 20 20 projecting from the rod member, the pin being fixed thereto; and there is a slot 21 cut into the end of the bearing member 7 in which slot the pin 20 is adapted to move as the rod is revolved. The revolving motion 25 of the rod is limited, however, to the travel of the pin 20 from one end to the other of the slot 21 and this movement is such as to prevent the flange 18 from being turned into the spoon member.

20 In other respects, this device is operated like the first described form. The rod and spoon members are opened and a lock of hair is passed between them, whereupon the handles are pressed toward each other to press the hair between the rod and spoon. The rod member may then be turned or revolved while pressed against the hair, and this will cause the hair to feed between these members. When the rod is turned in one direction as 40 far as it will go, as shown in Figure 5, the flange will engage around one edge of the spoon member and apply heat to the outside of the reverse wave. The use of the revolving rod in this form of the device is as much 45 for the purpose of working the hair tightly into the spoon and causing the flange to press snugly against the outside of the spoon.

The iron shown in Figure 9 is similar to those previously described except that there 50 is a cable 22 for conducting electric current to a heater (not shown) which is disposed in the rod, the latter being made hollow for this purpose. The heater is not shown in the present case because it may be the same as the 55 heater shown in my said patent. The handle 23 attached to the rod member is adapted to be manipulated by the operator for the purpose of revolving the rod member the same as in the devices previously described.

60 If the cable 22 becomes twisted while the rod is being revolved in one direction it will generally be unwound when the rod is reversed. Even if the operator in the course 65 of waving the hair, does not have occasion to reverse the rod member, nevertheless the cable

may be unwound by revolving the rod member for that purpose without necessarily turning the iron as a whole. This cable straightening feature of the revolvable rod is 70 obviously only available in the plain type of iron and not in the flange type of iron shown in Figures 4, 5 and 7 because in the latter the rod member is only allowed to turn a limited extent.

It will be apparent that I have provided a 75 curling iron the rod of which is not only adapted to be revolved, but the operator is able to manipulate one of the handles for the purpose of revolving the rod member for any desired reason whether it be to simply work 80 the hair closely into the spoon member or to close the flange of the flange iron tightly on the edge of the spoon member or to cause the hair to be worked through between the spoon and rod members to make a wider wave. 85

Having described my invention, what I claim is:

1. A curling iron including a spoon member and a rod member pivotally connected with each other to co-operate in pressing a 90 lock of hair between them, handles for said spoon and rod members by which they may be pivotally operated, said rod member being adapted to be revolved on its own axis in relation to the spoon member by revolving the 95 handle which is associated with said rod member.

2. A curling iron including a spoon member and a rod member, a bearing member through which the rod member extends and 100 in which the rod member is adapted to revolve on its own axis in relation to the spoon member, said bearing member being pivotally connected with the spoon member whereby the rod member and the spoon member may pivot in relation to each other to co-operate in pressing a lock of hair between them, said spoon and rod members having handles, the rod member being adapted to 105 revolve in said bearing member relatively to the spoon member when said rod member handle is revolved.

3. A curling iron including a spoon member and a rod member, said spoon member having a yoke, a bearing member through 110 which the rod member extends and in which it is adapted to revolve on its own axis, said bearing member being disposed between the arms of said yoke and pivoted thereto, said spoon and rod members having handles by 115 which said members may be operated to clamp a lock of hair between them, said rod member being adapted to be revolved in said bearing member by the operation of its handle.

4. A curling iron including a spoon member having a yoke and a handle projecting rearwardly from said yoke, a rod member co-operating with said spoon to clamp a 120 lock of hair between the spoon and rod mem- 125

ber, a bearing member in which said rod member is revolvably mounted, said bearing member being disposed between the arms of said yoke and pivoted thereto whereby the 5 rod member may both pivot and revolve on its own axis, said rod member having a rear extension including a handle in co-operative relation with the handle of the spoon member, said rod member being adapted to be 10 revolved in said bearing member by means of its said handle.

5. A curling iron including a spoon member having a yoke and a handle extending rearwardly therefrom, a rod member having 15 a bearing member mounted thereon in which the rod member is adapted to revolve on its own axis, said bearing member being disposed between the arms of said yoke and pivotally connected therewith, a collar on 20 said rod member adjacent one end of said bearing member, a sleeve on said rod member on the opposite side of said bearing member whereby the rod member is prevented from moving axially in relation to the bearing 25 member, said rod member having a handle extending rearwardly in co-operative relation with said first handle and adapted to be revolved for the purpose of revolving the rod member in said bearing member.

30 6. A curling iron including a spoon member having a concave side, a rod member having a portion adapted to project into the spoon member to engage a lock of hair between the spoon and rod members, said rod 35 member having a flange engaging around one side edge of said spoon member, means for pivotally connecting the rod and spoon members, said rod member being revolvable in relation to the curling iron, and a handle 40 on said rod member by means of which the latter may be revolved in relation to the spoon member.

7. A curling iron including a spoon member having a concave side, a rod member having a portion adapted to project into the spoon member to engage a lock of hair between the spoon and rod members, said rod member having a flange engaging around one side of said spoon member, means for 45 pivotally connecting the rod and spoon members, said rod member being revolvable in relation to the curling iron, a handle on said rod member by means of which the latter may be revolved in relation to the spoon member, and means for limiting the revolution of the rod member to prevent the said flange from entering the concave side of the spoon member.

8. A curling iron including a spoon member having a concave side, a rod member having a portion adapted to project into the spoon member to engage a lock of hair between the spoon and rod members, said rod member having a flange engaging around 50 one side edge of said spoon member, means

for pivotally connecting the rod and spoon members, said rod member being revolvable in relation to the curling iron, a handle on said rod member by means of which the latter may be revolved in relation to the spoon 70 member, a pin on said rod member, said bearing member having a groove in which said pin travels and wherein the pin is limited to confine the revolution of the rod member whereby the said flange will be prevented 75 from entering the concave side of the spoon member.

Signed at the city, county and State of New York, this 28th day of August, 1931.
